UNITED STATES PATENT OFFICE.

FRANCIS ARTHUR FRINGS, OF LONDON, ENGLAND.

DUPLEX PEN.

1,312,440.

Specification of Letters Patent. Patented Aug. 5, 1919.

Application filed March 24, 1919. Serial No. 284,822.

To all whom it may concern:

Be it known that I, FRANCIS ARTHUR FRINGS, a subject of the King of England, residing at London, England, have invented certain new and useful Improvements in Duplex Pens, of which the following is a specification.

This invention relates to duplex pens, that is to say duplex writing instruments whether pens, pencils, or styles of any kind, in which one "pen" is so carried upon the other as to be guided to slide relatively to the other and so that one writing point traces a line of writing above that traced by the other point.

According to the present invention, a duplex "pen" of the type defined and having relatively slidable "pens", is characterized by an operative connection between the two "pens" such that upward thrust of the one produces a downward thrust of the other relatively to the guiding element. The object of this is to cause the pressure of one "pen" upon the paper to determine the magnitude of the pressure of the other, irrespective of difference of level in the writing surfaces.

The said means connecting the two "pens" conveniently takes the form of a rocking lever carried by the guiding element and having pivotal engagement at one end with one "pen" and at the other end with the other "pen".

The present invention is further to be ascertained by reference to the accompanying drawings, in which—

Figure 1 is an elevation in part section of one construction;

Fig. 2 is a view similar to Fig. 1 of a modified construction;

Fig. 3 is an elevation in part section, and

Fig. 4 a plan of a device to receive the record made by one of the writing points.

In the construction shown in Fig. 1, pens A B are provided each with a tubular sheath A¹ B¹ respectively wherein the corresponding pen is mounted to slide freely, but without shake, in the direction of its length, and the two sheaths are connected by a clip C embracing the two sheaths.

Upon the body of each pen is a small lug, these being lettered A² and B² respectively, and to these lugs are pivoted the ends of a telescopic link D. The two portions of the link are slotted where they overlap one another, and at this part they engage a pivot-

pin D¹ which passes through the slots. The clip C connects the two sheaths A¹ and B¹ and provides for the link a pivotal axis at right-angles to the sliding movements of the pens in their sheaths.

A pivoted gripping-lever K is mounted upon the clip C so that it may be moved, as will readily be understood from the drawing, to grip the pen B within its sheath B¹ and lock it therein. The object of this is to lock the pen B out of action when it is not desired to write in duplicate. Any gripping arrangement may be employed and it may be applied to either pen or to any construction embodying the present invention.

The action of this construction, or of any mechanical equivalent thereof, is very advantageous, particularly where the pens are intended to be used one to write upon a surface higher than that upon which the other is writing. It will readily be seen that, as the user grips the mounting formed by the sheaths and clip, and causes them to approach the writing surface or surfaces, so soon as one pen strikes its surface it tends to be forced up into its sheath and so forces the other down by movement of the link about its pivot D¹; this action takes place irrespective of which pen it is that is the first to touch the surface. In further movements the pressure of one pen upon its writing surface is transmitted through the link to the other pen so that substantial equality of pressure on the two writing points is automatically maintained.

In an alternative construction shown in Fig. 2, a one-piece link E is employed pivoted upon a fixed pivot-pin E¹ carried in the clip C. The ends of the link are, however, slotted at E² and one end engages a pivot-pin A³ on one pen while the other end engages a pivot-pin B³ on the other pen. The action of this construction is the same as that of the other but the construction is slightly more simple.

A convenient means of presenting a record strip to the pen B is illustrated in Figs. 3 and 4. In this device, a box-like portion F incloses a roll of paper-strip G mounted on a spindle F¹ and a second spindle F² is provided, hereinafter called the "draw-off" spindle intended to receive the record when made. The spindle F² is operated by a thumb-lever H through a ratchet-wheel and spring-pawl H¹ H², and the paper is passed through a slot F³ in the bottom of the box

over a lip F^4 projecting rigidly from the front of the box. From this lip the paper is returned into the box through a slot in its front and passes on to the draw-off spindle H^1 ; guide-rolls J are provided where required. Any convenient construction may be adopted enabling the box to be opened for the insertion and withdrawal of the paper. In use, the box is held above the pen so that the writing point B makes a record on the paper above the lip F^4 , and when the paper here presented is sufficiently covered with record, corresponding with the record made with the pen A upon its writing surface, the strip of paper from G is moved by operation of the thumb-lever H .

The sheaths A^1 B^1 together with the clip C constitute what is herein described as the "guiding element" for the pens. Moreover, the term "rocking lever" is employed to denote a lever pivoted to rock about a point between its two effective ends.

It is to be understood that it is within the scope of this invention to provide any means for so interconnecting the "pens" each sliding within its guiding element that as a thrust is applied to the one tending to slide it in its guide, the other is thereby automatically thrust in the opposite direction. Furthermore, it may, in some cases, be desirable to provide unequal leverage between the

"pens" and this may readily be accomplished by suitably locating the pivot-pins D^1 E^1 or, if some other construction be employed, by modifying it accordingly. 3

What I claim as my invention and desire to secure by Letters Patent is:—

1. The combination with a clip, of a pair of parallel sheaths secured to said clip, a pair of writing members mounted in said sheaths, respectively, and having their writing points projecting therefrom, and a lever pivoted in said clip between said writing members and having its opposite arms engaging said writing members whereby the upward pressure on one writing point is caused to exert a downward pressure on the adjacent writing point or vice versa, substantially as described. 40

2. The combination with a clip, of a pair of parallel sheaths secured to said clip, a pair of writing members mounted in said sheaths, respectively, and having their writing points projecting therefrom, and a telescopic rocking lever pivotally supported upon the said clip, and having pivotal engagement at one of its ends with one of said members, and at the other end with the other of said members, substantially as described. 55

In testimony whereof I affix my signature. 60

FRANCIS ARTHUR FRINGS.
